UNITED STATES PATENT OFFICE.

DANIEL W. MCNEIL, OF CINCINNATI, OHIO, ASSIGNOR TO THE JOHN DOUGLAS COMPANY, OF CINCINNATI, OHIO, A CORPORATION OF OHIO.

NON-SCALDING SHOWER-BATH COCK.

942,405.

Specification of Letters Patent. Patented Dec. 7, 1909.

Application filed August 14, 1908. Serial No. 448,464.

To all whom it may concern:

Be it known that I, DANIEL W. MCNEIL, a citizen of the United States of America, and resident of Cincinnati, county of Hamilton, State of Ohio, have invented certain new and useful Improvements in Non-Scalding Shower-Bath Cocks, of which the following is a specification.

My invention relates to shower bath cocks which regulate the flow of hot and cold water to the shower by means of the movement of one handle.

My invention is especially adapted for use in a system of baths wherein there are a series of adjacent showers. Heretofore there have been in use cocks for regulating the flow of cold, medium or hot water from the shower, by means of the movement of a single handle, which, in its initial movement would open the cold water, upon the further movement would admit hot water to be mixed with the cold, and upon a still further movement would increase the proportion of the hot water in comparison with that of the cold. But, in these cocks heretofore used, should one bather have turned the handle to an extent such as to cause a flow of warm water, and a person in the adjacent shower should suddenly turn on the cold water, this sudden demand upon the cold water supply flowing to the first shower, would reduce the supply to an extent such that the relative proportion of the cold to the hot water would be so small, that the first bather would be scalded. The cocks heretofore used have been open likewise to certain objections of construction, such that the wearing of the parts would render the supply of water difficult of regulation.

It is the object of my invention to provide a non-scalding shower bath cock, which will have an automatic means of stopping the flow of water should a sudden demand be made upon the cold water supply of one cock, and to supply a cock the parts of which are little liable to wear, and in which the operation is not so much affected by any wearing of the parts. This object is attained by the means described in the specification and illustrated in the accompanying drawings, in which,

Figure 1 is a sectional view of a cock embodying my invention taken upon line $x-x$ of Fig. 3. Fig. 2 is a sectional view taken

upon line $y-y$ of Fig. 1. Fig. 3 is a sectional view taken upon line $v-v$ of Fig. 1.

Referring to the parts: The valve casing is divided by suitable partitions into a cold water chamber, a , a hot water chamber b , an elongated mixing chamber, c , an exit chamber, d , and a pressure chamber, e . Cold water is to be led into chamber, a , by means of pipe, a' , and hot water is to be led into chamber, b , by pipe, b' . The water is to be led from the exit chamber, d , to the showers by means of a pipe, d' .

Between the cold water chamber, a , and the mixing chamber, c , is a valve seat, a^2 , against which a valve, A , is seated. Between the hot water chamber, b , and the mixing chamber, c , is a valve seat, b^2 , against which valve, B , is seated. Between the exit chamber, d , and the mixing chamber, c , a valve seat is formed by means of a ring, d^2 , with the internal bore of which piston valve, D , has a sliding but watertight contact. Between the exit chamber, d , and compression chamber, e , a valve seat e' , is formed, against which a disk, d^3 , seats. Disk, d^3 , is formed integral with the valve stem d^4 , of the piston valve, D . The valve stem, d^4 , has secured upon it a cup, d^5 , which contacts the walls of the compression chamber, e , which is connected by means of a branch pipe, e^2 , with the cold water pipe, a' , the entrance of the pipe, e^2 , being between the end wall of the chamber, e , and the cup, d^5 . The pipes, a' , and b' , have valve seats formed in their ends against which check valves, a^3 , and b^3 , are seated.

The means of moving the valves are as follows: The valve casing, F , has a bonnet, F' , secured upon it, the internal screw-threads of which, are engaged by the screw-threads of a collar, g , formed integral with the main valve stem, G , to which the hand-wheel, G' , is secured. Valve stem, G , stands in alinement with the piston valve, D , which is held in contact with the valve stem, G , by the pressure of the water in the chamber, e . Valve stem, G , has adjacent to the collar, g , screw-threads, g' , whose pitch is greater than that of the pitch of the screw-threads, g , being made preferably twice the pitch. Within the elongated mixing chamber, c , is a yoke, H , whose ends have screw-threaded recesses, to receive screws, a^4 and b^4 , to which the stems, a^5 and b^5 of the valves, A and B , are secured respectively.

Stem, a^5 , has adjacent to the valve, A, a reduced portion, a^7 , of a diameter less than the diameter of the valve seat, a^2 , and adjacent to the yoke, a collar, a^8 , of a diameter greater than the valve seat, a^2 . The stem of valve, B, has a portion, b^7 , adjacent to the valve of a diameter equal to the diameter of the valve seat, b^2 , and adjacent to the yoke a part, b^8 , of a less diameter than the diameter of the valve seat, b^2 . Yoke, H, is internally screw-threaded to fit the screws, g' .

Valve casing, F, has openings in alignment with the screws, a^4 and b^4 , and the valves, A and B. These openings are closed 15 by screw-threaded caps, f , f' , f^2 and f^3 , respectively. The caps, f^2 , f^3 , have guides, f^4 , f^5 , for the stems, a^6 , and b^6 , of the valves, A and B, respectively.

The operation is as follows: In Fig. 1 20 the cock is shown in its closed position, viz. the stem, G, occupies a position such that the disk, D, closes the opening between the mixing chamber, c, and the exit chamber, d, and the valves, A and B, are both seated. When 25 the handle, G', is rotated to the left, it carries the valve stem, G, in a direction away from valve seat, d^2 . The pressure of water in the chamber, c, causes the valve, D, to follow the valve stem, G, so that the disk, D, passes 30 beyond the valve seat, d^2 , and opens the communication between the mixing chamber, c, and the exit chamber, d. The rotation of the valve stem, G, causes the yoke, H, to move downward upon the valve stem, G, a 35 distance twice that of the movement of the valve stem outward from the valve seat, d^2 .

The result is that the valves, A and B, are moved inward away from the valve seats, a^2 and b^2 . The movement of the valve, A, 40 brings the reduced portion, a^7 , of the stem within the opening of the valve seat, so that cold water flows from the chamber, a, into the mixing chamber and thence into the exit chamber. The enlargement, b^7 , of the stem 45 of the hot water valve, fills the opening in the valve seat, b^2 , and prevents the passage of hot water into the mixing chamber. Upon a further rotation of the hand-wheel, G', in the same direction, the tapered part of the 50 valve stem, b^7 , will come adjacent to the valve seat, b^2 , so that hot water will then pass into the mixing chamber to be admixed with the cold water. A further rotation of the hand-wheel, G', will draw the tapered 55 part, a^8 of the valve stem, a^5 , toward the valve seat, a^2 , thus diminishing the cold water supply, while the reduced portion, b^8 , of the hot water valve stem stands within the valve seat, b^2 , thus increasing the relative amount 60 of hot to cold water. When the rotation of the valve stem has brought the enlargement, a^8 , to seat against the valve-seat, a^2 , it is seen that the water passing into the exit chamber, d, will be only that from the hot 65 water chamber, b.

The pressure in the cold water chamber, a, and the compression chamber, e, is the same because of their communication through the branch pipe, e^2 . Should the supply of water to the pipe, a' , be suddenly reduced by 70 reason of the opening of the cold water valve in an adjacent shower, this reduction of pressure is promptly effected in the compression chamber, e, and the pressure in the mixing and exit chambers will then carry 75 the valve disk, D, to its seat, d^2 , closing the communication between the mixing chamber and the exit chamber and cutting off the discharge of the shower, so that a bather 80 could not be scalded.

The function of the check valve, a^3 , is to prevent the water from the mixing chamber flowing into the cold water chamber, a, and thence into the compression chamber, e, when a reduction of pressure in the last 85 named chamber occurs.

What I claim is:

1. In a hot and cold water cock, the combination of a valve casing having a mixing chamber and an exit chamber communicating with the mixing chamber, cold and hot water valves adapted to regulate the flow of water to the mixing chamber, a third valve for controlling the communication between the exit and the mixing chambers, and a 90 means of communicating the pressure of the cold water to the third valve to carry it away from its seat, whereby when the pressure of the cold water to the cock is diminished, the third valve closes the communication 95 between the mixing and the exit chamber.

2. In a hot and cold water cock, the combination of a casing having a hot water chamber, a cold water chamber, a mixing chamber and an exit chamber, hot and cold water valves in the casing and adapted to regulate the communication between the hot and cold water chambers and the mixing chamber, a third valve adapted to regulate the communication between the mixing and the exit chambers, a yoke, means of coupling the hot and cold water valves to the yoke, a valve stem having two sets of differential screw-threads, one engaging the casing, the other set engaging the yoke, and means of communicating the movement of the stem to the third valve to carry it toward its seat, whereby the movement of the valve stem regulates the positions of the hot and cold water valves and the third valve.

3. In a hot and cold water cock the combination of a casing having within it an elongated mixing chamber, a hot water chamber, a cold water chamber and an exit chamber upon the same side of the mixing chamber, the wall between said chambers having openings in it, a hot water, a cold water and an exit valve seated against the respective openings, a main actuating stem 125 130

and a means of connecting it with the valves whereby the movement of the stem simultaneously moves the three said valves.

4. In a hot and cold water cock the combination of a casing having within it an elongated mixing chamber, a hot water chamber, a cold water chamber and an exit chamber upon the same side of the mixing chamber, the wall between said chambers 10 having openings in it, a hot water, a cold

water and an exit valve seated against the respective openings, a yoke, means of connecting it to the hot and cold water valves, a differential screw engaging the casing and the yoke, and means of causing the exit 15 valve to move with the screw.
